CLAIM

I claim the ornamental design for an outsole for a shoe, as shown and described.

DESCRIPTION

FIG. 1 is a bottom view of an outsole for a shoe showing my new design;

FIG. 2 is a right side view thereof;

FIG. 3 is a left side view thereof;

FIG. 4 is a front view thereof;

FIG. 5 is a rear view thereof;

FIG. 6 is an enlarged fragmentary perspective view of the area referenced as “6” in FIG. 1; and,

FIG. 7 is an enlarged cross sectional view taken on line 7—7 of FIG. 6, the broken lines forming no part of the claim.

The broken lines showing a shoe upper in FIGS. 2–6 illustrate the portion of the design that forms no part of the claim. The two separate patterns shown on the surfaces of the enlarged fragmentary perspective view of FIG. 6 are understood to extend across their entire circumscribed areas, throughout the views.
